UNITED STATES PATENT OFFICE.

HAROLD W. SHONNARD, OF MONTCLAIR, NEW JERSEY, ASSIGNOR TO ELEVATOR SUPPLIES COMPANY, INC., A CORPORATION OF NEW JERSEY.

DOOR-OPERATING MEANS.

Application filed February 9, 1926. Serial No. 86,986.

The present invention relates to an improved form of automatic door closers for use in connection with the doors or gates used at the various floors along an elevator shaft, as well as to certain improvements in the apparatus for controlling the electric safety circuits largely used in elevator practice in connection with the doors at the various floors.

10. The principal object of my improved door closer is the provision of apparatus which can be largely assembled in the factory, and which is so arranged as to occupy a minimum of space both in the horizontal dimension parallel to the planes of movement of the doors and at right angles thereto.

In order to economize valuable space, many elevator shafts are so constructed as to afford practically no room at all for doors or door closers beyond the space taken up by the elevator cage, in a horizontal direction in the planes of movement of the sliding doors. Moreover, in certain instances the width of the sill plate is restricted to three and three-quarters inches; and, where the room afforded is so confined, it is not possible to install the styles of sliding doors heretofore in use together with the necessary door controlling apparatus.

30. The present invention provides a form of door closer and checking means which can be successfully installed in elevator shafts offering only the restricted space above specified, and at the same time this is accomplished by means which can be largely assembled in the factory, thereby effecting a great saving in time and labor in actual installation. This is accomplished by fixing the supporting plate to which the door operator is pivoted upon the free face of the closing device, and allowing the doors to slide in under the closing device, and inside of the aforesaid supporting plate.

The invention is illustrated in a preferred embodiment by way of example in the accompanying drawings, wherein Figure 1 is a view in elevation of a part of a door, with the closer and master interlock or safety switch, Figure 2 is a similar view of one side of the door when in open position, Figure 3 is an end view of the same and Figure 4 is a view in elevation on a larger scale of my preferred master safety switch.

In Figures 1 and 2 the two sliding doors at a given floor on an elevator shaft are

shown at 10 and 11. The door 10 is suspended from hangers 12 adapted to roll along the guide bar or rail 13.

Above the level of the doors and at one side of the door opening is fixed the automatic door operator 14, preferably of the type in which the door closing element proper is combined with means for checking the final door movement in both opening and closing to prevent slamming. This is a well-known device the details of which are not a part of the present invention.

A supporting plate 15 is fixed to the outer face of the door closer 14, and extends down along one side of the door opening, as shown to a point about opposite the middle of the doors 10 and 11.

The sliding back and forth of the door 10 is accomplished by means of the locking toggle arms 16 and 17, pivotally connected with the door 10 at 19, and the arm 17 is similarly connected with and supported by the plates 15 at 20. An extension 21 of the arm 16 forms a handle whereby the toggle arms are manually brought into the position shown in Figure 2 in opening the door.

The closing of the door is accomplished in a well-known manner by means within the closer 14, which act through the arm 22, and the connecting bar 23 pivotally attached at one end to the arm 24 fixed at the other to an arm 24 fixed to the toggle arm 17. When the door is opened, as in Figure 2, the swinging catch 25 may be brought under a stop 26 to lock the parts in open position, preventing operation of the door closer.

As clearly shown in Figure 3, the sliding door 10, when in open position, moves under the door closer 14, and between the wall and the supporting plate 15. This is made possible by locating the supporting plate 15 on the outer face of the door closer, as shown and described.

At the bottom of Figure 3 is shown the sill plate, and from inspection of the vertical dotted line in Figure 3, it will be seen that my invention makes it possible for the doors and all the working parts connected therewith to be accommodated within a space inside of the shaft wall no wider than the sill 27.

My invention also makes it possible to assemble the door closing means, the toggles and the supporting plates for these latter at the factory, thereby eliminating a great deal

of time and labor in final assembly and preventing the possibility of many errors in measurement and location, leading to loss of time and money.

- 5 In many elevators, depending upon electric currents for operation it is customary to employ a master switch or interlock, generally near the top of the shaft, which insures the shutting of all doors before starting the elevator cage, by keeping the operative circuit open until the doors are shut. These are generally operated by a cable extending down alongside of the shaft which extends over an operating pulley at the 10 switch and has a weight attached to it. If the cable breaks or the weight becomes detached, such a master switch will fail to operate.

One feature of my invention is a means 20 for operating the master switch so contrived that if the cable breaks or the counterweight on the cable is disconnected, the switch will automatically go to open circuit position and the elevator cannot be moved.

- 25 The switch 28 may be of any well known construction the details of which are not here shown, and it is operated by an arm 29 connected by a rod 30 with a grooved wheel 31 over which passes a cord or chain 32. This last is continued down past all the doors in the shaft and is kept taut by a weight 33.

Opposite each door in the shaft, the cord, 35 rope or chain 32 carries a ball 34, or equivalent device, capable of engaging with an arm 35 on the connecting bar 28 operated by the door closer. When the doors are closed, as in Figure 1, the arm 35 descends, permitting the weight 33 to move the cord, 40 tape or chain downward and turn the wheel 31 so as to bring the arm 29 into the position shown in Figure 4, which closes circuit in the switch and permits the elevator to move.

- 45 When the door is opened as in Figure 2, the arm 35 lifts the ball 34 and weight 33, allowing the weight 36 on the wheel 31 to turn said wheel clockwise and so bring the arm 29 into the dotted line position in 50 Figure 4. This opens the circuit and pre-

vents operation of the elevator. The weight 36 has a smaller turning moment than the weight 33.

By attaching the weight 36 to the wheel 31, independently of the operating cord, 55 tape or chain 32, said weight will act to open the circuit at the switch 28 automatically in case the cord or chain should become detached.

It will be readily seen that certain advantages of my invention are applicable to doors operated entirely by hand, wherein the door closer is replaced by a door check to prevent slamming. By applying the supporting plate 15 to the free face of such a 60 door check, the saving of space achieved by my invention is attained. In my claims, therefore, the term "door operating device" is meant to apply either to a door closer, a 65 door check or a combination of the two as 70 illustrated herein.

A variety of changes may be made in this apparatus without departing from the scope of my invention, which is not limited to the 75 details herein shown and described.

What I claim is—

1. Apparatus of the character described comprising, a door operating device, a supporting plate fixed to the outer face thereof, a door adapted to slide under the door operating device inside of said supporting plate, and operative connections between the operating device and the door partly supported by said supporting plate.

2. Apparatus as in claim 1 wherein a toggle lever system is pivotally attached to the lower end of the supporting plate which system is operatively connected with the door operating device.

3. Apparatus as in claim 1 in combination with a horizontal supporting rail for the hangers of a sliding door, which rail is fixed to the door operating device on the side opposite the supporting plate and at right angles to it.

In testimony whereof I have hereto affixed my signature on this 8th day of February, 1926.

HAROLD W. SHONNARD.
